UNITED STATES PATENT OFFICE.

BOLESLAW WARCHALOWSKI, OF ILION, NEW YORK.

HATPIN.

1,370,388.

Specification of Letters Patent.

Patented Mar. 1, 1921.

Application filed June 14, 1920. Serial No. 388,956.

To all whom it may concern:

Be it known that I, BOLESLAW WARCHALOWSKI, a citizen of Poland, residing at Ilion, in the county of Herkimer and State 5 of New York, U. S. A., have invented certain new and useful Improvements in Hatpins; and I do declare the following to be a full, clear, and exact description of the invention, such as will enable others skilled 10 in the art to which it appertains to make and use the same.

This invention relates to an improved hat pin which is equipped with novel means for retaining the same in position in the crown 15 of a hat, thus preventing it from becoming accidentally lost.

One object of the invention is to provide a pin equipped with novel retaining members which are such that they do not interfere with the insertion of a pin, but prevent 20 accidental withdrawal thereof, that is, these members remain in ineffective position while the pin is being inserted, and automatically assume effective position in case 25 the pin is moved in a reversed direction.

Another object of the invention is to provide a hat pin, the shank of which is of a length to prevent the point thereof from projecting through the side of the crown of 30 the hat opposite to that side from which it is inserted as it ordinarily does, which feature of construction obviates the necessity of employment of a guard and serves to prevent possible injury of persons who 35 might contact the point of the pin.

A further object of the invention is to provide a hat pin which is equipped with a detachable head and foldable retaining members which are inclined toward the head 40 and are movable to effective position after the pin is inserted through the crown of a hat and is rotated.

A still further object of the invention is to generally improve upon hat pins provided 45 with loss preventing means by producing one which is novel and simple in construction, easy to manipulate, effective in use, and inexpensive to manufacture.

Other objects and advantages of the invention will be apparent during the course 50 of the following description.

In the accompanying drawings forming a part of this specification and in which like numerals are employed to designate like 55 parts throughout the same:

Figure 1 is a side elevational view of a

hat pin constructed in accordance with my invention.

Fig. 2 is an enlarged view thereof with the head removed and parts broken away to disclose the manner of mounting the foldable retaining members.

Fig. 3 is a top plan view of the intermediate portion of the pin and the retaining members.

Fig. 4 is a transverse sectional view taken on the line 4-4 of Fig. 2, looking in the direction of the arrows.

Fig. 5 is a detail perspective view of one of the retaining members.

Fig. 6 is an enlarged detail sectional view of the detachable head and its retaining means, illustrating the manner in which it is connected to the shank of the pin.

In carrying out my invention I employ a pointed hat pin which is provided intermediate its ends with foldable loss preventing means which is inclined away from the point and is normally ineffective, thus permitting the pin to be easily inserted. This means however, becomes effective in case the pin is moved in a direction reverse to that in which it is inserted. In addition to this means, the pin is also equipped with a detachable head held in place by any suitable means.

Referring to the drawings wherein the construction referred to is set forth in detail, it will be seen that the numeral 1 designates a pin, one end of which is pointed as shown at 2. Arranged between this end and the opposite end of the pin is novel retaining means for preventing loss of the pin from the hat. While this means may be of any other design, I desire to employ foldable arms 3 for the purpose, the same being pivoted in longitudinal spaced, transversely extending slots 5, and being foldable against the pin in the manner disclosed. The free ends of each of the arms 3 is twisted laterally as shown at 6, and it is this portion which rests against and surrounds approximately one-quarter of the entire circumference of the pin. These arms when in ineffective position incline away from the point 2, this construction permitting the pin to be inserted without interference of the arms, the latter coming into play when the pin is rotated, or moved in a direction opposite to that in which it is inserted.

Fitted on the opposite end of the pin is a detachable head 7. This head may be of

various constructions and may be retained on the pin in many ways. By preference, it includes a slot tubular member 8 for reception of the pin 1, and oppositely disposed 5 ears 9. Pivoted between the latter are hook-shaped latch arms 10, the heads of which engage the transverse slot 11 and retain the head on the pin. A spring 12 is employed for the purpose of retaining the latch arms 10 in effective position.

At this point, I desire to mention that the length of the pin is such that when it is in position, the point thereof will not project through the opposite side of the crown 15 of a hat as it ordinary does. It is my idea in making the pin of this length, to obviate the necessity of the employment of a guard for the point of the pin. It is obvious that I am enabled to do this because the point 20 of the pin does not project through the crown of the hat, hence, there is no chance of persons being injured by the same, as oftentimes happens.

In use, the point 2 of the pin is forced 25 through one side of the crown of a hat in the usual way. During this operation, the foldable retaining arms 3 will remain in ineffective position and will not interfere with the easy and ready insertion of the 30 pin. Due to the length of the pin, the point will not project through the opposite side of the crown of the hat, for the reason already described. When the pin is in this 35 position, it may be rotated slightly to the right so as to move the arms 3 to effective position. Movement of the arms to this 40 position will occur due to the laterally twisted parts 6 with which they are equipped and which come into contact with the hair. It is obvious that when the arms are in 45 ineffective position, the pin cannot possibly become displaced. To remove the pin, it is necessary to first detach the head 7. This, as is obvious, is done by compressing the 50 ineffective ends of the latch arms 10. After the head is detached, the pin is moved in the same direction in which it is inserted until it drops down from engagement with the 55 crown of the hat, thus permitting removal of the latter. Now, the pin may be further moved in the same direction so as to move the retaining arms to ineffective position, after which it may be easily taken out of the hair. I desire to mention here, that it 60 is not always necessary to rotate the pin in order to bring the retaining arms to effective position because the latter will automatically move to such position in case the pin is moved in a direction reversed to 65 that in which it is inserted.

A careful consideration of the foregoing description taken in conjunction with the accompanying drawings will enable persons skilled in the art to which this invention relates to obtain a clear understanding of

the same, therefore, further description is deemed unnecessary.

It is to be understood that the form of the invention herein shown and described is to be taken as a preferred form of the same, 70 and that various minor changes in the shape, size, and arrangement of parts may be resorted to without departing from the spirit of the invention or the scope of the subjoined claims.

75

I claim:

1. A hat pin provided with an outwardly movable member which is normally folded tight against the pin throughout its length and remains in this position until the pin is 80 moved in a reverse direction, when it automatically assumes its effective position.

2. A hat pin provided with a plurality of longitudinally spaced slots, and a plurality of arms mounted on fixed pivots in said 85 slots for holding the pin in a hat, said arms being folded closely against the pin throughout their lengths when the latter is being inserted through the crown of a hat, and being automatically movable away from the 90 pin in case of withdrawal of the latter.

3. A hat pin provided with a plurality of foldable arms which are normally folded tight against the pin throughout their lengths and remain in this position until the 95 pin is moved in a reverse direction, when they automatically assume effective position and prevent accidental withdrawal of the pin.

4. A hat pin provided with a plurality of 100 longitudinally spaced slots, and a plurality of arms pivoted in the slots and foldable against the pin, the free end of each arm being twisted laterally so as to conform to the shape of the pin when it is folded against 105 the latter.

5. A hat pin equipped with loss preventing means and a transverse slot; a removable slotted head for the pin, and a spring 110 retained catch arm pivoted on the head and movable through the adjacent slot and into the slot in the pin.

110

6. A pointed hat pin provided intermediate its ends with automatically operative loss preventing means which is ineffective 115 and disposed against the pin when the latter is inserted through the hat crown, but moved to effective position if the pin is moved in a reverse direction, and a detachable head on the pin to permit the same to be removed 120 by pushing it in the same direction in which it is inserted.

7. The structure specified in claim 6, said loss preventing means being a pivoted spur foldable throughout its length against the 125 pin.

8. A pointed hat pin provided with laterally disposed projections inclined from the point toward the head, whereby the pin must be inserted and removed by pushing it 130

in the same direction; and a detachable head on the pin.

9. The structure specified in claim 6, the loss preventing means being a plurality of 5 pivotally mounted longitudinally spaced arms.

10. A pointed hat pin of uniform diameter throughout its length, automatically operative loss preventing means on the pin in-

termediate the ends thereof, permitting the 10 pin to be inserted through the crown of the hat without injuring it, and a quick detachable head on the non-pointed end of the pin, permitting the latter to be inserted and removed by pushing it in the same direction. 15

In testimony whereof I have hereunto set my hand.

BOLESLAW WARCHALOWSKI.
